UNITED STATES PATENT OFFICE

148,608

DESIGN FOR A COMBINED AQUARIUM AND COFFEE TABLE

Alden D. Bullock, Seattle, Wash.

Application February 20, 1946, Serial No. 126,734

Term of patent 7 years

(Cl. D33—14)

To all whom it may concern:

Be it known that I, Alden D. Bullock, a citizen of the United States and a resident of Seattle, in the county of King and State of Washington, have invented a new, original, and ornamental Design for a Combined Aquarium and Coffee Table, of which the following is a specification, reference being had to the accompanying drawing, forming a part thereof.

In said drawing:

The single figure is a perspective view of a combined aquarium and coffee table showing my new design.

I claim:

The ornamental design for a combined aquarium and coffee table, as shown.

ALDEN D. BULLOCK.
